UNITED STATES PATENT OFFICE

AGNES G. SWEET, OF PAWTUCKET, RHODE ISLAND

CIGARETTE HOLDER

Application filed November 4, 1930. Serial No. 493,428.

This invention relates to improvements in cigarette holders and comprises a handle portion having formed at one end thereof a stationary jaw of an arcuately curved shape in cross section and pivotally secured against the stationary jaw is a movable jaw, normally held into engagement with the stationary jaw by means of a spring or other resilient member. The invention also comprises a device having a modified handle which may be removably secured to the jaw members whereby handles of different colors may be supplied to the jaw members to match corresponding shades of materials worn by ladies, whereby a lady smoker may attach to the jaw members a handle of a suitable color or shade to blend or match the colors of her wearing apparel.

A further object of this invention, is to provide a device of the above mentioned character having an ornamental form adapted to extend over the movable or pivoted jaw member to conceal the working parts thereof and the tension member or spring.

A still further object of this invention is to provide a cigarette holder adapted to embrace a cigarette or the like whereby the smoker's hands will not become soiled with nicotine ensuing from the smoke from the cigarette.

Other objects and advantages of the invention will become apparent during the course of the following description, forming a part of this specification and in which,

Figure 1 is a top elevation of an embodiment of this invention, illustrating the handle portion and the movable jaw member embracing a cigarette which is shown in dotted lines;

Figure 2 is a side elevation of the invention illustrating the arrangement of the jaw members and the arrangement of the ornamental form for covering and concealing the operative parts and the unfinished portion of the movable jaw operator;

Figure 3 is a side elevation of the invention similar to Figure 2, illustrating the jaws separated ready for the insertion of the smoking process or cigarette;

Figure 4 shows an enlarged detail view of the device illustrated in Figures 1 to 3 inclusive, showing the jaw members in cross-section, taken on lines 4-4 of Figure 1 and illustrating a removable handle and the manner in which the same is secured to the stationary jaw member;

Figure 5 is a transverse cross-sectional view taken on lines 5-5 of Figure 2 illustrating the pivotal joints between the clamping or jaw members; and

Figure 6 is a modified form of the device illustrating the same in side elevation and showing the handle as being formed integral with one of the jaw members.

In the drawing, wherein for the purpose of illustration and wherein like reference characters are employed to designate like parts throughout the same, the reference character 5 will generally be employed to designate a handle having a reduced grip portion 6, having a reduced screw threaded portion 7 adapted to be received in a corresponding screw threaded opening 8 of a jaw member 9. The jaw member 9 may be formed of metal while the handle 5 may be formed of a suitable light material colored to produce the desired effect. The jaw member 9 is provided with an arcuately curved jaw 10 formed integral therewith, having an arcuately curved inner section 11 to fit the contour of a cigarette. The jaw member 9 is further provided with a slotted portion 12 forming extensions 13 on opposite sides of the slot 12 for pivotally receiving a jaw 14 as at 15. The jaw 14 is provided with an extension 16 which is adapted to align with the slot 12 whereby the same may be received therein when the jaws 10 and 14 are opened and the extension 16 depressed. A coil spring or other resilient member 17 may be provided for normally holding the jaw 14 in close relation to the jaw 10, whereby a cigarette designated by the reference character C may be frictionally held there between.

Secured to the extension 16 as by means of rivets 18 is an ornamental plate 19 having a gem mounting 20 thereon for holding and receiving a gem 21 which may be of a corresponding color to the handle 5.

The jaw 14 is provided with a reduced portion 22 adapted to be received between the furcated member 9, whereby lateral movement of the jaw 14 and extension 16 may be prevented while opening or closing the jaw and operating the finger piece or extension 16.

In the modified form of the invention illustrated in Figure 6, the device includes a handle 5' of any desired configuration in which the jaw member 9' is formed integral therewith as is also the arcuately curved jaw 10'. The movable jaw 14' is formed on the finger piece 16' and the pivot pin 15' is employed for pivotally holding the pivoted jaw 14' to the extension jaw member 9'. The ornamental plate is of the same character as illustrated in Figures 1 to 4 inclusive as is also the gem setting 20 and gem 21.

It is to be understood, that various changes in the shape, size and arrangement of parts may be resorted to without departing from the spirit of the invention or the scope of the subjoined claim and that the form of the invention herewith shown and described is to be taken as a preferred embodiment of the same.

Having thus described the invention, what I claim is:—

A device of the character described comprising an elongated handle, a stationary jaw member having a shank screw threadedly secured to the handle, said shank having a longitudinal slot therein, a movable jaw having an extension adapted to be received in said slot, a pivot pin passing through the shank and through the extension whereby the movable jaw may be pivotally carried by the shank, an extension formed on the movable jaw for operating the same, a coil spring interposed between the shank and extension for normally holding the movable jaw in closed relation with the stationary jaw and means carried by the extension adapted to partially cover and conceal the operative part of the extension and shank and serve as an operating finger piece.

In testimony whereof I affix my signature.

AGNES G. SWEET.
